(57) **CLAIM**

The ornamental design for a drink container lid assembly, as shown and described.

DESCRIPTION

FIG. 1 is a top front right isometric view of a drink container lid assembly showing the design.

FIG. 2 is a bottom rear left isometric view of the drink container lid assembly of FIG. 1.

FIG. 3 is a front elevation view of the drink container lid assembly of FIG. 1.

FIG. 4 is a rear elevation view of the drink container lid assembly of FIG. 1.

FIG. 5 is a left elevation view of the drink container lid assembly of FIG. 1.

FIG. 6 is a right elevation view of the drink container lid assembly of FIG. 1.

FIG. 7 is a top plan view of the drink container lid assembly of FIG. 1.

FIG. 8 is a bottom plan view of the drink container lid assembly of FIG. 1.

FIG. 9 is a top front right isometric view of the drink container lid assembly of FIG. 1 in an open configuration.

FIG. 10 is a top plan view of the drink container lid assembly of FIG. 9.

FIG. 11 is a top front right isometric view of a lid assembly of the drink container lid assembly of FIG. 1.

FIG. 12 is a bottom rear left isometric view of the lid assembly of the drink container lid assembly of FIG. 11.

FIG. 13 is a front elevation view of the lid assembly of the drink container lid assembly of FIG. 11.

FIG. 14 is a rear elevation view of the lid assembly of the drink container lid assembly of FIG. 11.

FIG. 15 is a left elevation view of the lid assembly of the drink container lid assembly of FIG. 11.

FIG. 16 is a right elevation view of the lid assembly of the drink container lid assembly of FIG. 11.

(Continued)

FIG. 17 is a top plan view of the lid assembly of the drink container lid assembly of FIG. 11.

FIG. 18 is a bottom plan view of the lid assembly of the drink container lid assembly of FIG. 11.

FIG. 19 is a top front right isometric view of the lid assembly of the drink container lid assembly of FIG. 11 in an open configuration; and,

FIG. 20 is a top plan view of the lid assembly of the drink container lid assembly of FIG. 19.

The dashed lines in the drawings illustrate portions of the drink container lid assembly that form no part of the claimed design. The shading lines shown in the drawings represent the approximate three-dimensional contour of the claimed design and are not intended to indicate surface decoration.
